(57) **CLAIM**

The ornamental design for a disk rotor hub of disk brake for vehicles, as shown.

DESCRIPTION

FIG. 1 is a perspective view of the rear and one side of a disk rotor hub of disk brake for vehicles showing my new design; FIG. 2 is a side elevational view thereof;

FIG. 3 is a side elevational view of the opposite side thereof;

FIG. 4 is a top plan view thereof;

FIG. 5 is a bottom plan view thereof;

FIG. 6 is a rear elevational view thereof; and,

FIG. 7 is a front elevational view thereof.
